INVERSE FEEDBACK CIRCUIT

Dudley E. Foster, South Orange, N. J., assignor to
Radio Corporation of America, a corporation of
Delaware

Application March 30, 1940, Serial No. 326,913

3 Claims. (Cl. 179—171)

The present invention relates to vacuum tube amplifiers of the type in which inverse or negative feedback is employed, and more particularly to an improved amplifier circuit of this type wherein the range of frequency over which there is obtained a constant degree of feedback is extended.

It is known in the prior art to employ a cathode impedance, included in both the input and output circuits of an amplifier, for producing degeneration or negative feedback. The effect of degenerative feedback is to extend somewhat the frequency range of an amplifier, decrease non-linear distortion and to increase the input impedance of the amplifier. In the prior art, particularly that directed towards obtaining an increased input impedance, or a value of input impedance which is substantially constant despite variations in grid bias of the amplifier tube, an unbypassed resistor has been used as the degenerative impedance connected to the cathode. A resistor is satisfactory when the frequencies it is desired to degenerate are low or when the frequency range to be degenerated is small. However, when constant degeneration is desired over a wide range of frequencies the effect of the inherent cathode to ground capacitance of the tube cannot be disregarded despite the fact that such capacitances are usually only a few micromicrofarads. They may be, for example, of the order of 5 to 20 $\mu\mu$ f.

I have found that with degenerative amplifiers of the type above mentioned the degree of feedback falls off to an appreciable extent with increasing frequencies. This is brought about by the shunting effect of the inherent cathode to ground capacity.

It is therefore one of the main objects of my invention to extend the frequency range over which a good degree of feedback is obtained, and I accomplish this by the use of an inductance coil in series with the cathode resistor which tends to eliminate, minimize or compensate for the effect of the inherent capacity which is effective between cathode and ground.

Another object of my invention is to vary the input impedance as well as the gain of the amplifier in a desired manner by suitable choice of values for the resistive and inductive components constituting the degenerative impedance.

The novel features characteristic of my invention are set forth with particularity in the appended claims. The invention itself, however, both as to its organization and mode of operation together with additional objects and advantages thereof will best be understood by reference to the following description taken in connection with the accompanying drawing in which

Fig. 1 discloses an inverse or negative feedback circuit embodying my invention, and

Fig. 2 are plots of several curves which show the variation with frequency of the input impedance of an amplifier circuit embodying my invention as compared to the conventional amplifier circuit.

Referring now to Fig. 1, the amplifier comprises an electron discharge tube T shown as of the pentode type although a triode or a screen grid tube may equally as well be employed. A tuned input circuit L_1-C_1 is connected between the signal control grid G_s and cathode K and a similarly tuned output circuit L_3-C_3 is connected between the plate or anode P and cathode. Connected to the cathode are the serially arranged resistor R_2 and inductance coil L_2 which are included in the common portion of the input and output circuits. The capacity inherent between the cathode K and ground is represented by the dotted line condenser C_2 .

20 The degenerative effect on the tube gain may be expressed as a change in effective mutual conductance of the tube, as will now be demonstrated. Employing the following symbols:

25 S_m , mutual conductance of tube without degeneration,
 S'_m , effective mutual conductance of tube with degeneration,
 Z_l , impedance of output load, L_3-C_3 ,
 e , input voltage across L_1-C_1 ,
 e_g , input voltage between signal grid G_s and cathode K,
 e_o , output voltage across L_3-C_3 ,
 Z_k , impedance connected to cathode K,
 Z_{in} , input impedance of tube without degeneration (i. e. $Z_k=0$), and
30 Z'_{in} , input impedance of tube with degeneration, then, if the plate impedance of the tube is high compared to the load impedance Z_l , as is usually the case,

$$e = e_g + e_g S_m Z_k$$

$$e = e_g (1 + S_m Z_k)$$

$$e_o = e_g S_m Z_l$$

$$\text{Gain} = \frac{e_o}{e} = \frac{S_m Z_l}{1 + S_m Z_k} = S'_m Z_l$$

$$S'_m = \frac{S_m}{1 + S_m Z_k}$$

40 50 Similarly, if the input current be i_1 ,

$$Z'_{in} = \frac{e}{i_1}$$

$$Z_{in} = \frac{e_g}{i_1}$$

$$e = e_g (1 + S_m Z_k)$$

$$\frac{Z'_{in}}{Z_{in}} = \frac{e}{e_g} = 1 + S_m Z_k$$

$$Z'_{in} = Z_{in} (1 + S_m Z_k)$$

The factor $1+S_m Z_k$ or its reciprocal is thus seen to be a measure of the degeneration in so far as it affects gain or input impedance. Since S_m is independent of frequency if Z_k be likewise independent of frequency over the desired range the degeneration will be independent of frequency over that range.

When a cathode resistor only is used for degeneration Z_k will vary inappreciably over the range where the inherent cathode to ground capacity reactance of the tube is very large compared to R_2 . However, when the capacity reactance of C_2 , here designated X_{C_2} , becomes appreciable compared with R_2 , Z_k decreases as shown by curve *a* of Fig. 2.

Now, if inductance L_2 be added in series with R_2 the effect of C_2 on Z_k may be nullified up to a desired limiting frequency. Specifically if R_2 be made equal to X_{C_2} at the highest frequency for which uniform or constant degeneration is desired and the reactance of L_2 , i. e. X_{L_2} , be made equal to

$$\frac{R_2}{2}$$

at that same frequency, Z_k will be invariable with frequency up to that limiting frequency value. The value of Z_k will under these conditions be as shown by curve *b* of Fig. 2. If L_2 be made larger Z_k will then vary with frequency as shown by curve *c* of Fig. 2.

Therefore, by discrete choice of L_2 in comparison with R_2 and C_2 , the effect of C_2 on Z_k may be nullified, or as is shown in curve *c* even reversed in direction of variation with frequency.

While I have shown and described a preferred embodiment of my invention, it will be understood that modifications and changes may be made without departing from the spirit and scope of the invention, as will be understood by those skilled in the art.

What I claim is:

1. An amplifier circuit comprising an electron discharge tube having cathode, control grid and

plate electrodes, a resistor connected to the cathode and included in both the grid to cathode and plate to cathode circuits whereby degenerative feedback occurs, and an inductance coil included in the cathode circuit resonating with the capacity inherent between cathode and ground at the high end of the frequency range of the amplifier, whereby a substantially constant degree of degeneration up to substantially the limit of the frequency range is obtained.

2. A high frequency amplifier circuit operating over a desired frequency range, comprising an electron discharge tube having at least cathode, control grid and plate electrodes, a resistor and an inductance connected in series in the cathode lead of said tube and included in both the control grid to cathode and plate to cathode circuits whereby degenerative feedback occurs, said resistor having a value equal to the reactance of the inherent capacitance existing between cathode and ground at the highest frequency of the desired operating range, and said inductance having a reactance of half that of the inherent capacitance at the said highest frequency.

3. A degenerative amplifier stage comprising an impedance in the cathode circuit thereof, the impedance consisting of a capacitance between cathode and ground and in parallel therewith a series arrangement of a resistor and an inductance, the magnitudes of said resistor, inductance and capacitance being so chosen that the resultant cathode circuit impedance is substantially constant over a desired frequency range, said magnitudes having the relation

$$X_{L_2} = \frac{R_2}{2} \text{ and } X_{C_2} = R_2$$

where R_2 is the value of the resistor and X_{L_2} and X_{C_2} are respectively the reactance of the inductance and the reactance of the capacity inherent between cathode and ground at substantially the highest frequency in the desired frequency range.
